SAFETY ATTACHMENT FOR ELEVATORS.

No. 337,768.

Patented Mar. 9, 1886.

UNITED STATES PATENT OFFICE.

THOMAS MARVIN HUNTER, OF NEW YORK, N. Y., ASSIGNOR OF ONE-HALF
TO WILLIAM J. BEST AND LOUISE JORDAN, BOTH OF SAME PLACE.

SAFETY ATTACHMENT FOR ELEVATORS.

SPECIFICATION forming part of Letters Patent No. 337,768, dated March 9, 1886.

Application filed December 30, 1885. Serial No. 187,075. (No model.)

To all whom it may concern:

Be it known that I, THOMAS MARVIN HUNTER, a citizen of the United States, and a resident of New York, in the county of New York and State of New York, have invented certain new and useful Improvements in Safety Attachments for Elevators; and I do hereby declare that the following is a full, clear, and exact description of the invention, which will enable others skilled in the art to which it appertains to make and use the same, reference being had to the accompanying drawings, which form a part of this specification, and in which—

15 Figure 1 is a side view or elevation of a portion of one side of an elevator-well equipped with my improved safety attachment. Fig. 2 is a vertical sectional view of the same, taken on the line $x x$ in Fig. 1. Fig. 3 is a side view 20 of one of the safety stops or dogs detached. Fig. 4 is a detail view showing in perspective the constituent parts of the safety-rail in which the dogs are pivoted. Fig. 5 is a vertical sectional view of the elevator-car, showing in elevation a portion of the side of the elevator-well, parts having been broken away for the purpose of illustrating the construction more clearly. Fig. 6 is a horizontal sectional view taken on the line $x x$ in Fig. 5. Fig. 7 is a 25 vertical sectional view taken on the line $y y$ in Fig. 6, and Fig. 8 is a perspective view illustrating means whereby the safety attachment will be operated automatically in case of breakage of the cable.

30 35 The same letters refer to the same parts in all the figures.

This invention relates to safety stops or dogs for passenger and other elevators, inclined-plane railways, and the like; and it has for 40 its object to provide a device which shall operate with certainty and form a positive stop for the purpose of automatically arresting the descent of the car in case of the operating apparatus becoming fractured or disarranged, 45 thereby preventing any destructive fall of the car and the danger and damage resulting therefrom.

With these ends in view the invention consists in the improved construction, arrangement, and combination of parts, which will 50

be hereinafter fully described, and particularly pointed out in the claims.

In the drawings hereto annexed, A A designate the vertical side beams of an elevator-well, upon which are secured vertical guide-rails B B, of ordinary construction.

C is the safety-rail, which is secured to one of the vertical side beams, in front of and parallel to the guide-rail. The said safety-rail is composed of a series of sections, D, E, and F, 60 arranged with relation to each other as shown in the drawings hereto annexed. Section D consists of a base-plate, G, having at its rear edge a vertical flange, H, the face of which is provided at its upper and lower ends with 65 recesses or shoulders I. The upper end of the flange H and the corresponding portion of the base-plate has a transverse notch, J, and the lower end of the flange and base-plate is beveled, as shown at K K, so as to form a triangular projection or extension, L. The section E, which forms a continuation of the base-plate between two sections, D D, consists of a flat plate of hard iron, the upper end of 70 which is provided with a triangular recess, 75 M, to receive the projection L, at the lower end of the section D. The lower end of the plate forming the section E is provided with a triangular tooth or extension, N, adapted to enter the notch J in the section D next 80 below. The plate E is provided with a perforation or opening, O, to receive the inner end of the bolt upon which the safety-dog is pivoted, as will be presently described.

The section F consists of a plate adapted to 85 be seated in the recesses, or against the shoulders I I of two adjoining sections, where it is firmly bolted or otherwise secured flush with the faces of the flanges H of said sections. Said plate is provided with a forwardly-extending lug, P, having a transverse perforation, Q, registering with the opening O in the plate or section E. The openings O and Q form the bearings for the bolt R of the dog S, which will be presently more fully described. By this construction of the "safety-rail," as I have called it, it may be easily constructed in small or short sections, bringing the dogs as closely together as may be desired. 95 The parts are so constructed as to brace each 100

other mutually, thereby insuring great strength, and the construction is simple and inexpensive, and the parts easily handled and put together.

- 5 The dog S, which is shown in detail in Fig. 3 of the drawing, consists of a body, a, having a perforation or pivot-hole, b, formed transversely therein, as shown. The main portion or weight of the body a is above and to one side of the pivot-hole, below and to the other side of which is a portion, c, which may be termed the "toe-piece," the extreme lower end of which has a recess, d, in which is journaled a friction-roller, e, the periphery of which extends beyond the toe-piece. At the lower end of the body portion a is formed a triangular heel, f. The upper end of the body a forms a flat surface, g, and its inner side has a recess, in which is seated a projecting cushion, h, of rubber or other suitable material. When the dog is placed in position, the heel f is seated or rests in the notch J at the upper end of the flange H of section D of the safety-rail, one dog being of course used for each such section.
- 10 25 The bolt R is then passed through the perforations O Q and the pivot-hole b, thus securing the dog in position for operation. The upper portion of the dog will by its own weight be tilted into the space or channel T between the guide-rail B and safety-rail C until the buffer h rests in contact with the former. The lower portion or toe-piece of the said dog will thus be tilted out in front of the flange H of the safety-rail.
- 30 35 U designates the elevator-car, the frame portion of which may be of any suitable construction. The lower portion of the frame is provided with grooved beams V V, forming guides for a frame, W, arranged to slide longitudinally in the said guides, and having a laterally-extending arm, X, extending through a slot, Y, in the outer one of said guides. Said arm carries a beveled block, Z, which, when the frame is pushed in an inward direction, is adapted to engage the toe-pieces of the safety-dogs, thereby throwing the upper ends of the latter in a forward direction between the plates E and F, and out of the way of the car. Normally, however, the
- 40 45 50 frame W is, by the action of a suitably-arranged spring, A', forced in an outward direction, the result of which is, that as the car descends the first dog encountered by the lower end of the guide-beam B' upon the outside of the car-frame will arrest the descent of the car. In order, therefore, to enable the frame W to be moved in an inward direction, so as to enable the descent of the car to take place under ordinary circumstances, mechanism is provided as follows:
- 55 60 Pivoted under the car-floor in a suitable hanger or bearing, C, is a bell-crank lever, D', the lower end or arm of which is connected by a suitable rod, E', with the inner end of the frame, while its horizontal arm forms a tread or bearing for a sliding foot-piece, F', extend-

ing vertically through the floor of the car. When it is desired that the car shall descend, the operator or attendant simply steps upon and depresses the foot-piece F', thus forcing the frame W in an inward direction against the tension of the spring A', and causing the block Z to strike the toes of and thereby disengage the successive pawls. In case of any accident, simply releasing the foot-piece F' will cause the frame W to be forced outwardly by the spring A', thereby causing the pawls to remain in operative position, so that the descent of the car will be checked by the first pawl which it encounters.

80 In Fig. 8 of the drawings I have shown mechanism by which the safety mechanism shall be thrown into action automatically and with absolute certainty in case of breakage of the supporting cable. The latter, which is denoted by letter G', is connected in the usual manner with the suspension-spring H' at the top of the car. Said spring is connected by a clip, I', with one end of a lever, J', the other end of which is connected by a rod or cord, K', with one arm of a bell-crank lever, L', the other arm of which bears against one end of a lever, M', the other end of which in turn bears against the rear or inner side of the arm X of the frame W. Under normal circumstances 95 this mechanism is inactive; but in case of breakage of the supporting-cable the lever M' will act to force the frame W in an outward or forward direction, or, in other words, into operative position.

100 From the foregoing description, taken in connection with the drawings hereto annexed, the operation and advantages of this invention will be readily understood. The construction is simple and inexpensive, and the operation is certain and efficient.

105 I would have it understood that in the construction of this device I do not limit myself to the precise construction herein claimed, but reserve to myself the right to all modifications which may be resorted to without departing from the spirit of my invention.

110 Having thus described my invention, I claim and desire to secure by Letters Patent of the United States—

115 1. In a safety attachment for elevators, the safety-rail consisting of sections D, E, and F, constructed and arranged substantially as and for the purpose herein shown and specified.

120 2. In a safety attachment for elevators, the herein-described safety-rail having sections D, provided with vertical flanges having notches at their upper ends to receive the heels of the safety-pawls, substantially as and for the purpose herein set forth.

125 3. In a safety attachment for elevators, the herein-described safety-rail, consisting of sections D, having flanges H, base-plates G, recesses I, notches J, and extensions L, the sections E, consisting of flat plates forming continuations of the base-plates of the sections D, and having recesses M and teeth N, and the

sections F, secured in the recesses I of adjoining sections D, substantially as and for the purpose set forth.

4. In a safety attachment for elevators, the safety-rail consisting of sections D, in combination with sections E and F, which conjointly form the bearings for the safety-dogs, substantially as herein described, for the purpose set forth.

10 5. In a safety attachment for elevators, the herein-described safety-rail, consisting of sections E and F, having bearings for the pivots of the safety-dogs, in combination with the intermediate supporting-sections, D, the upper 15 ends of which have transverse notches or recesses, in which the safety-dogs are supported when at rest, substantially as and for the purpose set forth.

6. In a safety attachment for elevators, the combination, with the safety-rail, constructed substantially as herein described, of the dogs pivoted between the sections E F of said safety-rail, and having upwardly - extending weighted bodies, heel-pieces, and projecting 25 toe-pieces provided with friction-rollers, sub-

stantially as herein described, for the purpose set forth.

7. In a safety attachment for elevators the combination, with a suitable safety-rail, of the herein-described dogs S, having body a, pivot-hole b, toe-piece c, recess d, friction-roller e, heel f, and cushion h, substantially as herein described, for the purpose set forth.

8. The combination, with the safety-rail, dogs, and car, constructed and relatively arranged substantially as described, and the supporting - cable G' and suspension - spring H', of the automatic operating mechanism consisting of the lever J', rod K', bell-crank L', and lever M', all arranged and operating substantially as herein described, for the purpose shown and specified.

In testimony that I claim the foregoing as my own I have hereunto affixed my signature in presence of two witnesses.

THOMAS MARVIN HUNTER.
